R. L. POE

STOVE AND FURNACE

Filed May 28, 1920

Inventor:
Robert L. Poe,

By Sheridan, Jones, Sheridan & Smith
Atty's.

UNITED STATES PATENT OFFICE.

ROBERT L. POE, OF CHICAGO, ILLINOIS.

STOVE AND FURNACE.

Application filed May 28, 1920. Serial No. 384,811.

To all whom it may concern:

Be it known that I, ROBERT L. POE, a citizen of the United States, residing at Chicago, in the county of Cook and State of Illinois, have invented certain new and useful Improvements in Stoves and Furnaces, of which the following is a specification.

This invention relates to improvements in stoves and furnaces, and more particularly to the fire-box linings thereof, the present improvements being designed primarily for use in connection with ranges such as disclosed in my prior co-pending applications Ser. Nos. 98,532 and 291,668, filed May 19, 1915, and April 21, 1919, respectively.

One of the important features in operation sought to be accomplished in these prior structures is the introduction of pre-heated air through the sides of the fire-box into the latter above the normal level of the fuel therein; to increase and promote combustion; and to effect a substantially complete consumption of the products of combustion as the latter rise from the bed of burning fuel.

Obviously, in order to accomplish these results it is necessary in the operation of these ranges to keep the level of the fuel therein below the openings through which the heated air is drawn, for otherwise the air supply would be cut off, and the combustion therefore rendered very inefficient. In practice it has been found that the persons ordinarily in charge of a range after its installation, even though explicitly instructed as to the manner in which it should be operated, do not exercise the requisite degree of care, oftentimes filling the fire-box to a level above the air outlet openings. This not only renders the combustion inefficient, by reason of the reduced air supply, but in a comparatively short time causes the fire-box lining to become over-heated, with the result that it is soon burned out. Furthermore, it has been found that after a fire-box has been filled several times above the air outlet openings, said openings very often become clogged or stopped up, so that the air supply is rendered negligible, even though the fuel level later falls below said openings. Another objection arising, due to carelessness in operation of these ranges, is the gradual filling up of the air circulation spaces on either side of the fire-box, by reason of small fragments of fuel, ashes, etc.,

dropping into these spaces through said outlet openings. All of these objections, as above indicated, are due to carelessness in operating, and not to any fault in the construction or design of the ranges.

The present invention contemplates an improved fire-box lining which, when installed in a range of the type above described, will avoid the objections above noted. Briefly stated, the invention comprises a multiple chamber fire-box lining, the outermost chamber of which is adapted to communicate with the air-heating passage of the range, openings of special design to prevent clogging thereof being provided in the lining for admitting the heated air from said passage into the fire-box, and the innermost chamber of the lining being provided with a bottom outlet leading into the ash-pit of the range to permit of fuel, ashes, etc., which may fall through said openings, dropping into said pit.

Other objects and advantages of the present improvements will become apparent from the following description, taken in connection with the accompanying drawings, wherein one form of the invention is illustrated.

Figure 1 is a vertical sectional view of a range, showing one form of the present improvements embodied therein;

Fig. 2 is a horizontal sectional view, taken on the line 2—2 of Fig. 1;

Fig. 3 is a front elevation of one of the fire-box lining members;

Fig. 4 is a vertical sectional view, taken on the line 4—4 of Fig. 3; and

Fig. 5 is a sectional view, taken on the line 5—5 of Fig. 3.

Referring more in detail to the drawings, the range comprises an outer casing 10, having front and rear walls 10^a and 10^b, respectively, and end walls 10^c and 10^d. Located within the casing are one or more ovens 11 extending from the front to the rear wall of the casing and spaced at their sides, top, and bottom from each other and from the casing, to provide circulation spaces for the hot gases. Extending along the bottom of the range, substantially from one end of the casing to the other, is an air-heating passage 12, supported on the top plate of which, near one end of the casing, are two upstanding plates 13, which form the side walls of the ash-pit 14. These side walls are spaced

- inwardly from the end wall of the casing and from the wall of the adjacent oven, respectively, so as to form air chambers 15, each of which communicates with the air heating passage 12 by means of a series of apertures 16 provided in the top plate of said passage, as clearly illustrated in Figs. 1 and 2. The side walls 13 are preferably held rigidly in position by means of bolts 17, or other suitable fastening elements, the bolts shown in the present disclosure being provided with spacing elements in the form of collars 18, through which said bolts extend.
- 15 Immediately above the ash-pit 14 of the range is the fire-box 19, the front and rear walls of the casing 10 forming the front and rear walls of said box as well as the front and rear walls of the ash-pit. The improved fire-box linings 20 form the side walls of the fire-box, these linings being preferably of cast metal and comprising substantially vertically disposed spaced apart walls 20^a and 20^b, and a rearwardly extending top wall or plate 20^c, this latter plate being designed for attachment to or connection with the adjacent structure of the range, as at 21 and 22, in order to aid in securing or holding the lining in proper position. The linings are preferably mounted in position within the range so that the walls 20^b thereof are in substantial alinement with the side walls 13 of the ash-pit, these walls of the lining units being preferably slightly longer than the walls 20^a, so that when the units are in position, as shown in Fig. 1, the lower edges of said walls 20^b overlap the upper edges of the walls 13 of the ash-pit and bear upon the spacing elements 18.
- 40 Interposed between the walls 20^a and 20^b of the linings are a plurality of spacing and reinforcing elements 20^d, the lowermost series of these elements of each unit coacting with the upper edges of the side walls 13 of the ash-pit in providing additional support for the linings. Projecting rearwardly from the walls 20^b of the units are further reinforcing elements 20^e, these elements being in the form of elongated ribs extending throughout the height of the linings and also serving as spacing elements when the linings are in position, by engaging the adjacent end wall of the casing in the one instance and the side wall of the adjacent oven in the other instance. These spacing ribs 20^e are preferably of such width as to maintain a close engagement between the ash-pit walls 13 and the walls 20^b of the units. The chambers or spaces intermediate the walls 20^b of the linings and the adjacent structure of the range constitute, in effect, continuations of the air chambers 15.
- 65 Elongated, horizontally disposed slots 20^f are provided in the walls 20^b of the linings near the lower edges thereof, and long, narrow, vertically disposed slots 20^g are provided in the walls 20^a, these slots extending from a point near the bottom of the fire-box upwardly and terminating in a series of outlet apertures 20^h above the normal level of 70 the fuel, this level being indicated by the dotted line 23.
- 75 The air-heating chamber 12 is provided at its far end with an air inlet 12^a, the air drawn through this inlet being very highly preheated during its travel through the passage 12 along the bottom of the range, from which passage said air passes upwardly through the openings 16 into the air chambers 15 on either side of the ash-pit and 80 fire-box, in which chambers said air is further heated especially during its travel adjacent the fire-box linings. This highly heated air is then drawn through the openings 20ⁱ in the plates or walls 20^b of the linings, and out into the fire-box through the outlet slots and apertures 20^g and 20^h, respectively. The air admitted into the fire-box below the fuel level tends to enhance the combustion of the fuel proper, while the 90 air admitted into said box above said level serves to effect a substantially complete consumption of the products of combustion as the latter rise from the bed of burning fuel.
- 95 In order to prevent the formation of a dead air space in the upper portions of the air chambers 15, adjacent the top plates 20^c of the linings, a series of apertures 20^j are provided in each of the plates 20^b just below said top plates, so that any heated air which 100 may pass above the openings 20ⁱ may pass through said apertures and into the fire-box along with the other currents of air. Each of the side linings is provided, intermediate the front and rear walls of the fire-box, 105 with an outstanding lug 24, which lugs are designed to receive and support the rear of the fire grate 25, the front end of said grate being supported in the usual manner (not shown) by means of a pin projected through the front wall of the casing and engaging a suitable recess in the front transverse bar of the grate. The portions of the grate which engage the lugs 24 are arched out so as to, in effect, pivot on said lugs when the 110 pin supporting the front end of the grate is withdrawn. In this manner the contents of the fire-box are dumped, it merely being necessary in replacing the grate in operative position to press down on the rear end thereof with a poker, or other suitable tool, so that the grate pivots on the lugs and the front end thus raised to proper position for receiving the retaining or supporting pin.
- 115 120 125 From the construction of the fire-box linings, and their arrangement within the range relative to the ash pit and the air chambers on either side thereof, it will be apparent that side linings for the fire-box are pro-

vided, comprising substantially three-spaced apart walls forming inner and outer vertically disposed chambers, the latter forming continuations of the air chambers 15 and the former opening into the ash-pit along the lower edge of the lining. Openings are provided in the walls 20^a and 20^b of the linings to permit of the passage of heated air from the air chambers into the fire-box, as above described, while the inner chambers opening downwardly into the ash-pit permit of all fragments of fuel ashes, &c., which may fall through the outlet openings 20^c and 20^d provided in the plates 20^a of the linings dropping into the ash-pit, thereby precluding the possibility of the air chambers or the openings, forming communication between said chambers and the air passage 12, becoming clogged or filled up. The long, narrow outlet slots provided in the linings serve to admit air into and above the fuel in the fire-box, resulting in very desirable advantages in combustion and the consumption of the products thereof. The walls of the outlet slots 20^e are preferably tapered rearwardly, or away from the fire-box, so that the outlet portions of such slots are more restricted than the rear portions thereof, and in this manner clogging of said slots is prevented.

30 The hot gases driven off from the fire-box are passed around the ovens prior to their passage through the flue 26, the usual damper 27 being provided for regulating the draft, and a damper 28 is provided to regulate or control the passage of the hot gases around the ovens.

Each side lining is preferably made up of a plurality of sections secured in position, as shown, although it will be readily understood that if desired the sections may be made sufficiently long so that only one will be required on each side. While fire linings of the present improvements have been described and shown in connection with a range, it will be obvious to those skilled in the art that the same are of more general use and adaptation, and that they may with slight change be used in stoves and furnaces generally. It will also be obvious to those skilled in the art that the present improvements are susceptible of various changes and modifications within the spirit of the invention; and it is therefore not desired to limit the same to the particular form or arrangement herein described and illustrated, except as defined in the appended claims.

I claim:—

60 1. The combination in a range having a fire-box and ash-pit, of air chambers on either side of said box and pit communicating with a bottom air-heating passage, and a hollow lining for said fire-box opening along its bottom into said pit and through its rear walls into said air chambers, the front walls of said lining being pro-

vided with openings leading into said fire-box.

2. A fire-box lining comprising spaced apart front and rear walls, openings in both said walls to permit of the circulation of air from behind said lining through the same and into said fire-box, the spaces between said walls opening along the lower edge of said lining exteriorly thereof to permit of the escape of fuel and ashes which may drop through the front wall openings.

3. In a range, a casing, an oven mounted therein, an air passage extending along the bottom of said range beneath said oven, an ash-pit spaced from said oven and the end wall of said casing to provide air chambers, openings in said air passage providing communication between the latter and said chambers, an inlet at the far end of said passage, a fire-box mounted above said ash-pit and having side linings spaced from said oven and said end wall of the casing, respectively, to provide continuations of said air chambers, chambers in said linings intermediate said air chambers and fire-box, said lining chambers opening into said ash-pit, and openings in said linings providing communication between said air chambers and the interior of said fire-box.

4. In a stove, a multiple chamber fire-box lining, said chambers opening along their lower edges, one communicating with the ash-pit and the other with an air-heating passage of said stove, and openings in the walls of said lining for admitting the heated air from said passage into the fire-box.

5. In combination, a casing, a fire-box, an ash-pit mounted therein, said fire-box having a triple walled lining, the walls being spaced apart to provide chambers, an air heating passage having an inlet at one end exterior of said casing and communicating with the outermost chamber of said lining at its other end, openings in the intermediate and inner walls of said lining to permit of heated air from said passage entering said fire-box, the inner chamber opening at its bottom into said ash-pit.

6. In a range, a casing, a fire-box and ash-pit mounted therein, the latter being spaced from the adjacent structure of the range to provide an air chamber an air-heating passage communicating with said chamber at one end and provided with an inlet at its other end, said fire-box being provided with a multiple-chamber lining, the innermost chamber thereof opening into said ash-pit and the outermost chamber communicating with said air chamber, and openings in said lining to permit of the circulation of heated air from said air chamber into said fire-box.

7. In a stove, a multiple chamber fire-box lining provided with means for admitting air from its outermost chamber into the fire-

box and having an outlet in its innermost chamber adapted to open into the ash-pit of said stove.

8. The combination in a stove having a fire-box, ash-pit and air heating passage, of a lining for said fire-box having two substantially vertically disposed chambers one opening into said ash-pit and the other communicating with said passage, and openings in said lining to permit of air passing therethrough from said passage into said fire-box.

9. In a stove, a fire-box lining having spaced apart walls forming a chamber, the latter opening into the ash-pit of said stove, means for supplying heated air to said chamber through the outer wall thereof, and a plurality of openings in the inner wall of said chamber to admit said heated air into the fire-box. 15

In testimony whereof, I have subscribed my name.

ROBERT L. POE. 20
